Patented Dec. 1, 1914.

Fig. 1.

UNITED STATES PATENT OFFICE.

GUSTAV DIECKMANN, OF SAN FRANCISCO, CALIFORNIA.

FOLDING BOX.

1,119,071.

Specification of Letters Patent.

Patented Dec. 1, 1914.

Application filed July 12, 1912, Serial No. 708,942. Renewed April 2, 1913. Serial No. 758,487.

To all whom it may concern:

Be it known that I, GUSTAV DIECKMANN, a citizen of the United States, residing in the city and county of San Francisco and State of California, have invented new and useful Improvements in Folding Boxes, of which the following is a specification.

This invention relates to a folding box, and particularly pertains to a device for locking the box in its open or its folded position.

It is the object of this invention to provide a box or crate which may be folded so as to occupy a comparatively small space when not in use, thus facilitating handling, storing and shipping the box when empty.

A further object is to provide a simple and efficient means for rigidly locking the box or crate in its open or closed position.

Another object is to provide a foldable box which is strong and durable, and which may be easily and quickly closed into its folded position, and unfolded into its open position.

The invention primarily resides in forming a box or crate with hinged sides and ends, with a removable top, and providing means for locking the sides and ends together in their open position, means for attaching the top to the sides and ends, and means by which the sides, ends and top of the box or crate may be securely clamped to the bottom thereof in a folded position.

The invention further consists of the parts and the construction and combination of parts as hereinafter more fully described and claimed, having reference to the accompanying drawings, in which—

Figure 1 is a perspective view of the box in its open position. Fig. 2 is a similar view showing the box in a partially folded position. Fig. 3 is a detail in elevation with parts broken away, showing the device for clamping the sides, ends and top of the box together. Fig. 4 is a vertical section on the line X—X of Fig. 3. Fig. 5 is a horizontal section on the line Y—Y of Fig. 3.

In the drawings A represents the bottom of the box which is rectangular in outline and which may be of any suitable proportions and construction. Mounted on the underside of the bottom A and extending transversely thereacross at its ends, are cleats 2 which serve as spacing members to support the bottom A clear of the surface upon which the box rests.

Formed on the longitudinal edges of the bottom A are upwardly extending flanges 3, on which the sides 4 of the box are hingedly mounted by means of hinges B; the sides 4 being pivoted to swing inwardly and to have a limited outward movement. The end panels 5 of the box are hingedly connected to the upper face of the bottom A by means of hinges C, to swing inwardly so as to rest on the bottom A between the flanges 3, when in their folded position. The end panels 5 are formed at their ends with longitudinally extending grooves 6, which are designed to engage ribs or tongues 7 formed on the inner faces of the side panels 4, adjacent their ends. The side panels 4 are designed to have sufficient outward movement from their vertical position to admit of the ribs or tongues 7 being inserted in the grooves 6 on the end panels 5, when the latter are in a vertical position; the bottom edges of the side panels 4 being beveled on their outer edge to permit of this outward movement.

Mounted on the outer ends of the side panels 4, a short distance from their upper edges, are inwardly extending spring clamp members 8, formed with hook-shaped ends, and mounted on the upper corners of the end panels 5 are angle plates 9, which are designed to be engaged by the hooked portions of the spring clamp members 8 when the side and end panels are disposed in their vertical positions, as shown in Figs. 3 and 5; recesses 10 being formed in the end panels 5 within the angle formed by the plates 9 to admit of the insertion of the fingers to facilitate grasping the ends of the spring clamp members to disengage them from the plates 9.

The top or cover of the box is indicated at 11, and is here shown as constructed of slats mounted on cleats 12 which extend transversely of the cover adjacent its ends; the cleats 12 being designed to contact the inner faces of the end panels 5 when the cover is placed on the box to prevent longitudinal movement thereof. The outer ends of the cleats 12 are cut away to form shoulders 13, which engage the side panels 4 of the box, as shown in Fig. 3, to prevent sidewise movement of the cover.

Mounted on the outer ends of the cover 11 are downwardly extending spring clamp members 14, which are formed with hook-shaped outer ends, and are designed to en-

gage the angle plates 9, as shown in Figs. 1, 3, and 4, to secure the cover 11 to the sides and ends of the box, when in its open position.

5 When it is desired to fold the box, the cover 11 is removed by disengaging the spring clamp members 14 from the angle plates 9. The cover 11 is then inverted and the bottom A is placed thereon with the 10 cleats 2 on the bottom A paralleling the cleats 12 on the top 11, as shown in Fig. 2. The spring clamp members 14 then extend upwardly adjacent the ends of the bottom A and engage the upper edge thereof, so as 15 to securely connect the cover 11 to the bottom A; the lower leaf of each hinge C forming a plate which is engaged by the hooked ends of the clamps 14. The spring clamp members 8 on the side panels 4 are then disengaged from the angle plates 9, and the 20 side panels 4 are sprung outwardly sufficiently far to disengage the ribs 7 from the grooves 6 on the end panels 5. This permits of the end panels 5 being then folded inwardly against the bottom A, as shown in 25 Fig. 2. The side panels 4 are then folded inwardly on top of the end panels 5; the flanges 3 being of such height as to allow the panels 4 to lie flat on the end panels 5. The 30 spring clamp members 8 now extending downwardly so that their hooked outer ends will engage the end edge of the bottom A and securely clamp the side members 4 to the bottom A in a folded position. Notches 35 15 are formed in the cleats 2 to admit of the spring clamp members 8 engaging the bottom A.

From the foregoing it will be seen that I have provided a box which may be folded 40 into a compact space and be securely clamped together in its folded position, and which may be easily and quickly unfolded into its open position by releasing the spring clamp members 8 from their engagement 45 with the bottom A and repositioning the sides and ends of the box in a vertical position, with the ribs 7 extending into the grooves 6 so as to retain the ends 5 in an upright position; the clamp members 8 being engaged with the angle plates 9 to hold 50 the side panels in tight contact with the end panels and prevent the sides being spread by the contents of the box.

When it is desired to use the box without 55 the cover 11, the latter may remain in its position on the bottom of the box, in readiness to be removed when its use is required.

It is to be observed that the angle plates 9 form a reinforcement and protection for 60 the corners of the end panels 5; corner plates 16 being mounted on the ends of the side panels 4, as a further provision for protecting the upper corners of the box against wear and damage.

65 Great strength and rigidity of the box,

when in its open position, is obtained by the combined use of the tongue and groove and the spring clamp connections; the tongue and groove joint serving to prevent the end panels being closed while the spring clamps 70 act to prevent the tongue and groove joint being separated, thereby effectively locking the side and end panels of the box together at the corners.

Having thus described my invention, what 75 I claim and desire to secure by Letters Patent, is—

1. In a foldable box having hinged side and end panels and a removable cover, means for fastening the side and end panels 80 and cover together, comprising angle plates mounted on the outer upper corners of the end panels, and spring clamp members carried by the side panels and cover, engageable with said angle plates. 85

2. A foldable box having inwardly swinging hinged side and end panels, said end panels formed with longitudinal grooves at their ends and recesses on their outer faces adjacent their upper corners, angle plates 90 on the end panels adjacent the recesses, ribs on the side panels engageable with the grooves on the end panels, and spring clamp members on the side panels engageable with the angle plates. 95

3. A foldable box having inwardly swinging hinged side and end panels, said end panels formed with longitudinal grooves at their ends and recesses on their outer faces adjacent their upper corners, angle plates 100 on the end panels adjacent the recesses, ribs on the side panels engageable with the grooves on the end panels, spring clamp members on the side panels engageable with the angle plates, a cover for the box, and 105 spring clamp members on the cover engageable with the angle plates.

4. A foldable box comprising in combination, a bottom, transverse cleats on the underside thereof, upwardly projecting flanges 110 on the longitudinal edges thereof, side panels hinged to said flanges, ribs on the inner faces of said side panels adjacent their ends, end panels hinged on the bottom to swing inwardly, having longitudinal grooves on their 115 ends for the reception of the ribs on the side panels, angle plates carried on the end panels adjacent their corners, spring clamp members carried by the side panels, engageable with the angle plates when the box is 120 in its open position, and engageable with the bottom of the box when it is in its folded position.

5. A foldable box comprising in combination, a bottom, transverse cleats on the underside thereof, upwardly projecting flanges 125 on the longitudinal edges thereof, side panels hinged to said flanges, ribs on the inner faces of said side panels adjacent their ends, end panels hinged on the bottom to swing 130

inwardly, having longitudinal grooves on their ends for the reception of the ribs on the side panels, angle plates carried on the end panels adjacent their corners, spring 5 clamp members carried by the side panels, engageable with the angle plates when the box is in its open position, and engageable with the bottom of the box when it is in its folded position, a removable cover for the 10 box, and spring clamp members on the cover engageable with the angle plates when the box is unfolded and engageable with the bottom of the box when folded.

6. A foldable box comprising in combination, a bottom, transverse cleats on the underside thereof, upwardly projecting flanges on the longitudinal edges thereof, side panels hinged to said flanges, ribs on the inner faces of said side panels adjacent their 15 ends, end panels hinged on the bottom to swing inwardly, having longitudinal grooves on their ends for the reception of the ribs on the side panels, angle plates carried on the end panels adjacent their corners, spring 20 clamp members carried by the side panels, engageable with the angle plates when the box is in its open position, and engageable with the bottom of the box when it is in its folded position, a removable cover for the 25 box, spring clamp members on the cover engageable with the angle plates when the box is unfolded and engageable with the bottom of the box when folded, and transverse 30 cleats on the cover engageable with the side and end panels to hold the cover against longitudinal and transverse movement.

7. In a foldable box, a bottom, sides hinged to the sides of the bottom, end panels 40 hinged to the ends of the bottom, a top, and fastening means depending from the top and being of a length for engagement with the end panels to hold the top in operative position, and when said top has its under face 45 seated against the under face of the bottom to have its said fastening means extend up from beneath the bottom to detachably engage the ends thereof.

8. In a foldable box, a bottom, sides 50 hinged to the sides of the bottom, end panels hinged to the ends of the bottom, a top, spring catches depending from the top, keepers on the end panels for engagement with

said catches to hold the top in operative position, said catches being of a length so that 55 when said top has its under face seated against the under face of the bottom said catches will extend from beneath the bottom to automatically snap over and engage the ends of the upper face of the bottom when 60 the end panels are in collapsed position.

9. In a foldable box, a bottom, sides hinged to the sides of the bottom, end panels hinged to the ends of the bottom, a removable cover, spring catches depending from 65 the cover and spring catches extending inwardly from the ends of the sides, and keepers on the end panels, said keepers having horizontal parts which engage the catches of the cover and vertical parts which engage 70 the catches of the sides.

10. In a foldable box, a bottom, sides hinged to the sides of the bottom, end panels hinged to the ends of the bottom, a removable cover, spring catches depending from 75 the cover and spring catches extending inwardly from the ends of the sides, and means on the end panels to engage the catches of the cover and sides, the catches of the sides when the parts are in folded position 80 engaging the under face of the bottom, and the cover being adapted to be placed beneath the bottom so that the cover catches will engage the upper face of the bottom.

11. In a foldable box, a bottom, sides 85 hinged to the sides of the bottom, end panels hinged to the ends of the bottom, a removable cover, spring catches depending from the cover and spring catches extending inwardly from the ends of the sides, said 90 catches having their free ends disposed adjacent to each other, the end panels having recesses therein each of which is common to and into which the free ends of a pair of adjacent catches project, and keeper means at 95 the marginal edges of each recess having horizontal parts to engage the cover catches and a vertical part to engage the side catches.

In testimony whereof I have hereunto set 100 my hand in the presence of two subscribing witnesses.

GUSTAV DIECKMANN.
